(57) **CLAIM**

The ornamental design for a toilet plunger handle with flange, as shown and described.

DESCRIPTION

FIG. 1 is a front elevation view of a toilet plunger handle with flange showing my new design attached to a plunger head;

FIG. 2 is a front elevation view of FIG. 1 without the plunger head;

FIG. 3 is a top plan view of FIG. 2;

FIG. 4 is a bottom plan view of FIG. 2 showing the hollow interior; and,

FIG. 5 is an enlarged partial view of the lower section of FIG. 2.

The broken lines showing portions of the toilet plunger handle in the drawings form no part of the claimed design. The radial and curved partial concentric lines in FIGS. 3 and 4 are to show only the contour of the claimed design and form no part of the claims.

No new matter is added by way of the present amendment.
